PROCESS FOR FORMING PLASTIC SOLUTIONS AND INCORPORATING SOLID FILLING MATERIAL THEREIN

Clarence E. Boutwell, Birmingham, Ala.

Application September 2, 1941, Serial No. 409,218

5 Claims. (Cl. 106—193)

This invention relates to a process for the rapid and thorough dispersion of plasticizers and cellulose into a solution, and for incorporating filling material into plastic solutions and the like, such as finely divided solid material in cellulosic plastics, phenolic-aldehyde resins, while in solution, and the like, and has for an object the provision of a process of the character designated which shall be effective to bring about a uniform dispersion of such material, in a minimum of time, in a liquid solution preparatory to forming a plastic into a solid, which dispersion shall be free of lumps or masses of unwetted solid material.

In my prior Patent No. 2,219,587, issued September 28, 1940, there is disclosed and claimed a printing plate composition comprising a cellulosic plastic material and a mineral filler up to approximately 30% by volume. By using ordinary mixing methods heretofore known to me, it has required from 24 to 48 hours to effect a thorough dispersion of the filling material in the plastic while in solution. By the process herein disclosed I have been enabled to reduce the time required for thorough mixing to from 3 to 4 hours, and have obtained a better, more complete dispersion.

In the carrying out of my invention I contemplate employing an excess of a volatile solvent such as acetone, alcohol, or a mixture of ether and alcohol, to aid in producing the dispersion, and removing and recovering the excess solvent as mixing proceeds to completion. I further contemplate introducing air into the mixture along with the solid material, to aid in the dispersion and to act as a vehicle in removing the volatile solvent from the mixture.

My invention further contemplates, in its preferred embodiment, a grinding action on the materials while they are being incorporated into the plastic solution whereby to provide a quicker, more thorough incorporation thereof into the liquid plastic solution and to insure against lumps, or masses of agglomerated material passing into the solution.

The single figure of the accompanying drawing, forming a part of this application, illustrates diagrammatically, by way of example, apparatus adapted to carry out my invention.

Referring to the drawing, I show a closed vessel 10, preferably having a hopper bottom as shown, for the mixture of solvent, plasticizers, plastic and filler. At 11 is shown a storage vessel for the solvent. A conduit 12 leads from the vessel 11 to the vessel 10, and a valve 13 in the

conduit 12 controls the flow of solvent to the vessel. A pipe 14 is connected to the bottom of the vessel 10 and has a control valve 16 therein. At 17 is a T connection to which a branch conduit 18 for the admission of solids into the mixture is connected, the branch conduit 18 being provided with a control valve 19. A funnel 21 is provided for feeding the material into the branch conduit 18.

At 22 I show a well known form of gear pump comprising, in its moving parts, an outside annular gear 23 and an inside spur gear 24 with a crescent shaped projection 26 extending from the casing and dividing the space between the two gears, as shown. The solution enters the casing of the pump 22 through the conduit 14 at 27, and is discharged at 28 into a conduit 29 which discharges it back into the vessel 10. As will be seen in the further description of my invention, a gear pump is preferably employed, due to its grinding action on the solid material passing therethrough. A gear pump of a form different from that herein shown may, of course, be employed, so long as it produces a circulation of the materials being mixed coupled with a grinding action on the solid material.

A conduit 30 is connected to the upper end of the vessel 10 and leads to a pump 31 which may be a rotary sliding vane pump, as shown. The pump 31 discharges through a conduit 35 to a condenser 32 into which a cooling solution is introduced at 33 and passes out at 34. A by-pass 36 having a valve 37 therein connects the conduits 30 and 35. This valve controls the flow of vapor from the vessel 10 to the condenser 32 when the pump 31 is not in operation. Condensate is collected in a vessel 38.

Assuming that the plastic employed is cellulose acetate and it is desired to incorporate therein a filler, such as lead carbonate or iron oxide, I proceed as follows: I first run into the vessel 10 a solvent, such as acetone, alcohol, or a mixture of ether and alcohol, in an amount about twice that required in the finished product before drying. The pump 22 is then started to bring about a circulation of the solvent through the pump and the piping system back into the vessel 10. The valve 37 is then opened and the required plasticizers are added through the funnel 21 and branch pipe 18 and are circulated through the pump 22 until thoroughly dissolved in the solvent. Next, the cellulose acetate is introduced into the confined stream of the solvent in the pipe 14 by feeding it slowly through

the branch conduit 18. In passing into the stream and through the pump 22, the minute particles of cellulose acetate are each exposed to the maximum quantity of solvent before they have an opportunity to agglomerate. Thus the cellulose acetate is thoroughly incorporated into the solvent and a smooth, uniform dispersion is made. I have found that the required amount of cellulose acetate may thus be thoroughly dissolved in the solvent in around 30 minutes. This time, of course, may vary with the size of the batch and the size and speed of the pump.

As soon as the cellulose acetate has been thoroughly dissolved, the filling material is introduced through the branch conduit 18, being added slowly, the rate of feed being controlled by the valve 19. This method of feeding the material into a confined stream of solution prevents agglomeration of masses of material which would otherwise have to be separated by heating. With a uniform feed of filling material introduced thus into the plastic solution, and with the pump 22 running, it will be seen that there must result a uniform dispersion of the solid material in the liquid. In addition, the action of the gears 23 and 24 grinds the solid material into the solution, prevents its lumping, and insures a thorough wetting of every particle of the solid material.

The action of the pump 22 creates a partial vacuum in the intake conduit 14, so that a considerable amount of air is drawn into the mixture with the materials added through the funnel 21. I have found that the air aids in the rapid mixing which I obtain, and also acts as a carrier for the solvent which is volatilized in the operation. It also increases the gaseous volume in the vessel 10. Accordingly, while the mixing is proceeding, the valve 37 is left open to permit the excess mixture of air and volatilized solvent to pass out of the vessel 10 to the condenser 32 where a cooling solution chills the solvent and condenses it for recovery in the vessel 38. When the mixing is completed, and with the circulating pump 22 still in operation, the valve 37 is closed and the pump 31 is started, creating a partial vacuum in the vessel 10 and drawing the solvent out of the mixture to be condensed in the condenser 32. By this procedure, I find that I recover about one-half of the original solvent employed, leaving the mixture of a consistency such that it may be spread upon a smooth plate to form a sheet, extruded, or otherwise treated, and dried to evaporate the remaining solvent and produce plates, sheets, rods, or whatever form the final product may take. It is understood, of course, that the solvent thus evaporated may be recovered, if desired, by well known means. When the mixing is completed, the contents of the vessel 10 may be discharged by means of a valve 40 connected to the conduit 14 directly beneath the vessel 10.

While the specific example given is a mixture of a cellulosic plastic, one or more solvents, plasticizers and solid filler material, other uses of my invention and other solid-liquid mixtures will at once suggest themselves to those skilled in the art that may advantageously be mixed in accordance with my invention. It is well known that the production of a uniform dispersion of a relatively high percentage of filling material in cellulose acetate, or other cellulosic plastics, with

methods heretofore employed, has required an excessive amount of time and care, with differing results in different batches. By my improved process, uniform results are obtained in all batches mixed, and in approximately one-tenth of the time heretofore required.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are specifically set forth in the appended claims.

What I claim is:

1. A process of incorporating solid filler material in plastics which comprises forming a solution of the plastic in a volatile solvent, forcibly circulating the solution in a confined restricted path, introducing solid filler material and grinding it into the solution while circulating in said path, maintaining a sub-atmospheric pressure in the path at the point of introduction of the solid material, and evaporating the solvent.

2. In a process of incorporating solid filler material in plastics, the steps which comprise forming a solution of the plastic, forcibly circulating the solution in a confined path, introducing solid filler material into the solution while circulating in said path, admitting air to the solution along with the solid material, separating air and volatilized solvent from the mixture, and condensing the solvent.

3. A process of incorporating solid filler material in plastics which comprises forming a solution of the plastic, forcibly circulating the solution in a confined path, introducing solid filler material into the solution while circulating in said path, admitting air to the solution along with the solid material, separating air and volatilized solvent from the mixture, condensing the solvent, and grinding the solid material into the solution as it is introduced therewith.

4. The method of forming a cellulosic plastic mixture containing up to 30% of solid mineral filler by volume, which comprises forcibly circulating a volatile solvent in a confined restricted path, adding cellulosic plastic to the solvent in said path and continuing the circulation until the plastic is thoroughly dissolved, slowly adding the solid material to the solution while circulating in said path, submitting the solid material to a grinding action while introducing it, continuing the circulation until the solid material is thoroughly dispersed and maintaining a partial vacuum in the restricted path at the point of introduction of the plastic and the solid material to induce a flow of air into the path at said point.

5. The method of forming a cellulosic plastic mixture containing up to 30% of solid mineral filler by volume, which comprises forcibly circulating a volatile solvent in a confined path, adding the cellulosic plastic to the solvent in said path and continuing the circulation until the plastic is thoroughly dissolved, slowly adding solid filler material to the solution while circulating in said path, admitting air into the solution along with the solid material, separating the air and volatilized solvent from the mixture, and condensing the solvent.
